UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,413, dated November 13, 1883.

Application filed August 23, 1883. Term of patent 3½ years.

To all whom it may concern:

Be it known that I, CATHERINE O'HARA, of the city, county, and State of New York, have invented and produced a new and original 5 Design for a Pattern of a Lady's Costume, numbered 8,859; and I do hereby declare that the engraved prints accompanying this specification convey to any one accustomed to using paper patterns a clear understanding of 10 how a garment made up by the pattern will appear.

The design combines a closely-fitted basque with a side-plaited skirt, a deep pointed drapery upon the front, and a deep, full, oval drap-

ery upon the back. The basque is of uniform 15 depth, with a cluster of tucks at each side of the closing in front, and has coat-sleeves and a standing collar. The skirt has a cluster of tucks and a deep hem at the bottom.

What I claim as my invention, and desire to 20 secure by Letters Patent, is—

The design for a lady's costume, as shown in the engraved prints accompanying this specification.

CATHERINE O'HARA.
